UNITED STATES PATENT OFFICE

EUGENE H. LESLIE AND EDWIN M. BAKER, OF ANN ARBOR, MICHIGAN

PROCESS OF AND APPARATUS FOR STEAM DISTILLATION

Application filed May 11, 1923. Serial No. 638,175.

This invention relates to a process of and an apparatus for steam distillation, and more particularly to a process and apparatus wherein petroleum oils or distillates may be distilled with the aid of steam.

The invention has as an object the provision of a process of and an apparatus for the steam distillation of solutions or mixtures, and the accomplishment of this object in a more efficient and economical manner than has heretofore been possible. A further object of the invention is to apply such a process to the distillation of petroleum oils or distillates and to recover various fractions therefrom.

In the present application there are described an apparatus and a process that are in many respects similar to the apparatus and process described in our co-pending application, Serial No. 626,274, filed Mar. 20, 1923; and specific reference is made to said application for a description of the general manner in which liquids and vapors are treated, and for the general theory of operation.

Reference is also made to our co-pending application, Serial No. 626,273, filed Mar. 20, 1923, for a description of the operation of the vaporizer disclosed therein, which is in many respects similar to the vaporizer employed in the practice of the present invention.

The preferred embodiment of the present invention is illustrated in the accompanying drawing, which forms a part of this specification; the figure of the drawing shows an apparatus for the continuous steam distillation of solutions or mixtures, particularly petroleum oils and distillates.

In said preferred embodiment of the invention, there is shown a fractionator 1, provided on its outer surface with a suitable lagging 2; and said fractionator is provided at the top with a vapor exit 3 leading to a reflux condenser 4, which may be operated either as a partial or a total condenser of the vapors. A pipe 5 is provided to lead away the uncondensed gases to a suitable absorber, and a reflux pipe 6 joins the bottom of the condenser to the top of the fractionator. The pipe 6 serves to convey the

condensed liquid to the top of the fractionator. A conduit 7 having a number of conduits 8 branching therefrom to the various sections of the fractionator, serves to conduct the hot liquid to the fractionator to be fractionated. Branch conduits 8 are preferably provided for each section and a valve is placed in each conduit, so that the hot liquid may be conducted to any desired section of the fractionator, or to two or more sections simultaneously. The fractionator is provided with any desired number of sections and the sections are provided with nipples 9 in order to permit liquid to descend from one section to the other, to permit vapors to ascend, and to cause liquid to accumulate on the plates of the sections. Means are provided to withdraw this liquid from any section as desired; said means comprising a number of pipes 10, provided with valves and connected to the sections as shown and leading to suitable receivers. A suitable packing material 11 is placed within the sections for the purpose of providing a very large surface of contact for the vapors and liquids, and this packing material may advantageously consist of ring or jackstone packings. Provision may also be made for the removal of gases by suitably connected pipes.

At the bottom of the fractionator is shown a pipe or conduit 12 that connects the fractionator to a vaporizer 13, which is operated to vaporize part of the liquid residue coming down the sections of the fractionator and passing through the conduit 12 into the vaporizer. A pipe-still 14 is connected to the vaporizer by means of pipes 15 and 16, the former serving to conduct the liquid residuum in the vaporizer to the still, and the latter serving to return it thereto in a heated condition. The pipe 16 may be provided with a pressure reducing valve 17, and the pipe 15 has positioned in its circuit a pump 18 which operates to circulate the liquid. The liquid delivered to the vaporizer strikes a baffle 19 from which the liquid spreads over a tower packing 20 and thence trickles downwardly through the packing zone. A second packing 21 is provided above the packing 20. A liquid exit 22 is connected to

the bottom of the vaporizer, and it is provided with a valve 23 operated by a suitable mechanism 24 that is controlled by a float 25 arranged as shown.

5 An open steam coil 26 is positioned in the lower portion of the vaporizer for the purpose of injecting steam into the liquid which collects therein.

The method of operation is as follows:

10 The oil, distillate, or other liquid or mixture is pumped through suitable heat exchange devices in which heat available in the residuum from the vaporizer, or from other source, is in part transferred to the incoming liquid. The latter then enters the manifold or conduit 7 and is introduced into any previously selected section of the fractionator. The choice of the section into which the liquid is introduced depends on the 15 nature and purpose of the distillation. If it is desired that the residuum from the still is to be free from the more volatile components of the liquid, but the distillate not entirely free from the less volatile components, the feed would be introduced into one of the upper sections of the fractionator. If it is desired that the distillate contain only the volatile components of the liquid and that the residuum need not be necessarily entirely 20 free from the volatile components, then the feed would be introduced into one of the lower sections of the fractionator. If both residuum and distillate must be sharply cut, the feed would be introduced into one of the 25 sections near the middle of the fractionator. It will be evident that the proper location of the feed section is in any case easily determined by trial.

30 In the fractionator, the process of change 40 of composition of descending liquid and ascending vapor is similar to that described in our co-pending application, Serial No. 626,274, but it differs in this respect, that two liquids mix and descend that portion of the fractionator below the feed section, these liquids being the feed liquid and the liquid running down the column from the reflux condenser at the top thereof. Otherwise the 45 changes and operations going on within the fractionator are substantially similar to those taking place in the fractionator of the above mentioned application.

50 The liquid flows from the bottom of the fractionator through the conduit 12 into the vaporizer 13 where it collects and is withdrawn through the pipe 15 by means of the pump 18, and forced through the heater coils of the pipe-still 14, the pipe 16, and the valve 17. Upon discharge upon the distributing 55 baffle-plate 19 it is spread over the surfaces of the packing 20, whereupon a portion of the liquid is vaporized. This vapor together with any that may have been formed in the heating-coils of the still, ascends through the 60 packing 21. During its passage through the

packing 21 entrained liquid droplets are removed as the result of impingement on the surfaces of the packing. The unvaporized liquid from the packing 20 together with downwardly flowing liquid from the fractionator collects in the bottom of the vaporizer 13.

70 Steam is introduced into the vaporizer 13 under the packing 20, and preferably through a perforated pipe 26 located near the bottom of the vaporizer and well beneath the surface of the liquid here collected.

75 Residual liquid is withdrawn from the bottom of the vaporizer through the pipe 22, and at a rate controlled by the valve 23 actuated by the float 25 and mechanism 24 as indicated in the drawing.

80 The steam and vapors resulting from the introduction of the steam, flow upwardly through the packing zones 20 and 21, where they mingle with the other vapors formed in and entering the vaporizer. The combined vapors pass through the conduit 12 to the fractionator for fractionation. The packing zones in the vaporizer also function in the fractionating process in some measure in a manner similar to that of the packed sections of the fractionator proper.

85 The fractionated products and water are removed either as vapors or as liquids from selected sections of the fractionator. If removed as vapors, condensers and coolers may be provided, and if removed as liquids it is desirable to provide coolers. It is preferable to remove the products as liquids since small piping may be used, and all condensing may be done in the condenser 4. It is preferable to perform all the condensing in said condenser, although if desired only a portion of the vapors may be condensed while the remainder is withdrawn. It is also preferable to remove the water as liquid water since in operating in this manner impurities and malodorous substances dissolved in the water are removed from the system.

90 Two important results are accomplished by the use of steam in distillation. First, the distillation can be conducted at a much lower temperature than if no steam is used, second, if the steam-distillation is conducted in such a manner that water as well as steam, is brought into intimate contact with the liquids and vapors within the distillation system, the odor of the products is usually improved as a result of the dissolving and extraction of malodorous substances by the liquid water. The hydrolytic effect of the warm liquid water may also result in improving the quality of the product.

95 Our process is designed to realize in practice the beneficial results attainable by a combined steam-distillation and fractionation process more effective and efficient than any used hitherto, and our apparatus provides a means for the practice of our process. It may 100

or may not be essential to our process of steam-distillation that fractionation occurs at the same time. However, it will usually be desirable to combine fractionation with steam-distillation; and our process is therefore designed to make this possible, in an effective and efficient manner.

While we have indicated the introduction of steam into the lower part of the vaporizer and prefer to introduce the steam at this point, it is obvious that similar results may be obtained by introducing either steam or liquid water into the vaporizer at some point other than the one indicated in the description of our preferred process, or into the pipe-still, for in each of these cases advantage would be taken of the partial-pressure effect of the water vapor, and steam would be caused to ascend into the fractionator. Also, less favorable results can be obtained by the introduction of steam or liquid water into the fractionator.

Our invention is applicable to the treatment of various liquids, and it may advantageously apply to the re-running or steam distillation of gasoline, to the reduction of kerosene to a desired flash point, to the reduction of lubricating distillates to the desired viscosity, and to the distillation and fractionation of petroleum oils, distillates, and products generally.

It is not essential to use a pipe-still, as other suitable heating means may be employed. A closed steam coil may also be positioned in the bottom of the vaporizer if so desired.

As many apparently widely different embodiments of our invention may be made without departing from the spirit thereof, it is understood that we do not limit ourselves to the embodiments described except as defined in the claims.

We claim:

1. A method of fractionating a petroleum oil comprising introducing it into a section of a fractionator, bringing ascending vapor into intimate contact with descending liquid, introducing condensed vapor at the top of the fractionator, collecting liquid in the sections, independently withdrawing liquid products from one or more sections, distributing the liquid residue from the fractionator over a confined packing zone to volatilize a portion of said liquid residue, allowing the unvolatilized portion to pass through another confined packing zone, injecting steam into the liquid flowing from the packing zones, and introducing volatilized vapors formed thereby into the bottom of the fractionator.

2. The method of fractionating mineral oil which comprises introducing such oil into a fractionating column having packed sections and allowing it to flow downwardly therein in contact with ascending oil vapors, condensing the vapor leaving the top of the fractionating column and refluxing condensate to the

column, collecting liquid in the column sections, withdrawing a liquid product from any desired section, vaporizing part of the liquid residue leaving the lower end of the column, returning resultant vapors to the lower end of the column, introducing steam into the unvaporized liquid residue from the vaporization to produce further vapors for introduction into the lower end of the column, and then further heating and subjecting to flash-vaporization the final liquid residue remaining from the steam distillation and introducing the resultant vapors into the bottom of the column.

3. A fractionator for treating petroleum oils comprising a number of superimposed sections containing packing material, a vaporizer having a vapor outlet connected to deliver vapor to the bottom of the fractionator and a liquid exit, packing zones between said outlet and exit, means for introducing steam into the bottom of the vaporizer, a heater for liquid, connected to receive liquid from the bottom of the vaporizer and to deliver heated liquid between the packing zones of the vaporizer, means for returning condensed vapor at the top of the fractionator, means for permitting the descent of liquids and the ascent of vapors and for collecting liquid in the sections, means for independently withdrawing liquids from one or more sections, and a conduit connected to one or more sections for delivering a liquid to the sections.

In testimony that we claim the foregoing, we have hereunto set out hand.
